SAUNA CABINET

John W. Kent, 4886 Marlette SE.,
Grand Rapids, Mich. 49508

Filed Sept. 16, 1968, Ser. No. 13,555

Term of patent 14 years

Int. Cl. D24—99

U.S. Cl. D83—1

FIG. 1

FIG. 5

FIG. 2

FIG. 3

FIG. 4

FIG. 1 is a perspective view of a sauna cabinet embodying my new design;

FIG. 2 is a top plan view of the sauna cabinet shown in FIG. 1;

FIG. 3 is a front view of the sauna cabinet shown in FIGS. 1 and 2;

FIG. 4 is a left side view of the cabinet shown in FIGS. 1, 2, and 3, the opposite side being identical; and

FIG. 5 is a perspective view similar to FIG. 1 showing the door in the open position.

I claim:

The ornamental design for a sauna cabinet, as shown and described.
